UNITED STATES PATENT OFFICE.

EDGAR G. HUBBEL, OF WINTHROP, MASSACHUSETTS.

TOOTH-BRUSH.

1,138,568.

Specification of Letters Patent. Patented May 4, 1915.

Application filed December 2, 1912. Serial No. 734,453.

To all whom it may concern:

Be it known that I, EDGAR G. HUBBEL, a citizen of the United States, residing at Winthrop, in the county of Suffolk, State of Massachusetts, have invented a certain new and useful Improvement in Tooth-Brushes, of which the following is a specification, reference being had therein to the accompanying drawings.

10 The invention relates to the class of tooth-brushes in which the bristle-block is removably combined with the handle.

It is an improvement upon the brush of U. S. Letters Patent No. 1,013,089 granted

15 to me under date of December 26, 1911.

The invention provides an improved backing or cover for the bristle-block, combines the former with the latter in improved manner, and provides novel means of securing 20 the backing or cover in working position whereby the removal and replacement of the same, conveniently and quickly, are facilitated.

An embodiment of the invention is illustrated in the drawings, in which latter,—

25 Figure 1 is a side view of a tooth-brush containing the said embodiment, on an enlarged scale, partly in section and with a portion of the handle broken out to reduce the length 30 of the handle. Fig. 2 is a top or plan view thereof, also with a portion of the handle in section and another portion broken out. Fig. 3 is a bottom view of the backing or cover, and Fig. 4 is an end view thereof. Fig. 5 is a view in vertical cross-section in 35 the plane of line 5, 5, Fig. 1.

Referring to the drawings,—the handle is marked 1, the bristle-block is marked 2, and the bristles are marked 3. As in the 40 patent mentioned, the bristle-block is removably combined with the handle by means of a projection 7 upon one end of the bristle-block, which is entered into a socket in one end of the handle, substantially as shown.

45 Preferably, the parts are secured together by threading the said projection and the inner surface of the wall of said socket, and screwing the projection into the socket. The wiring by which the tufts of bristles 50 are held in place in the holes therefor in the bristle-block is marked 6 in Fig. 1. At 13, 13, are the longitudinal slits or slots which extend vertically through the bristle-block to facilitate cleaning the bristles.

55 The backing or cover is marked 4. It extends over the upper surface of the bristle-

block and conceals the holes occupied by the tufts of bristles, the upper ends of said tufts, and the tuft-securing means. It is formed with slits or slots 14, 14, registering 60 with those formed in the bristle-block.

In accordance with the present invention I form the backing or cover 4 with a plain depending flange 4^a, so that when the bristle-block and cover have been assembled together the backing or cover incloses practically the entire bristle-block, and the edge of the latter is almost completely concealed by the said flange. In the present instance the said flange is vertical, and fits a correspondingly formed upper portion of the edge of the bristle-block. The vertical flange of the backing or cover incloses the lateral shoulders at the butt-end of the bristle-block, the inturned ends 4^b, 4^b, of 75 the said flange being separated just far enough to receive between them the screw-threaded stem 7 of the bristle-block. When the handle and bristle-block are screwed together, the adjacent end of the handle 80 abuts upon and covers and conceals these ends of the flange. Consequently said ends cannot scratch the mouth of the user of the brush.

The lower portion 2^a, of the bristle-block 85 projects outward relative to the lower edge of the flange 4^a, as shown in Figs. 1 and 5, so as to provide a shoulder which conceals and protects said edge, which makes close contact with the upper surface or shoulder 90 of the said projecting portion or lip 2^a.

The backing or cover is engaged with the tip-end of the bristle-block, so as to hold the tip-portions of the two in proper relations, by means of a pin, 2^b, Fig. 1, projecting from the tip-end of the bristle-block and entering a hole, 4^c, Figs. 3 and 4, in the corresponding portion of the flange. The backing or cover is furnished at its butt-end with a lug, 4^d, Figs. 1, 2 and 3, projecting horizontally 100 therefrom between the ends 4^b, 4^b, of the flange. This lug lies close against the flattened upper surface of the stem 7 of the bristle-block, and enters the chamber or socket in the handle together with the stem, 105 so that when the handle is screwed up tightly into place it operates by its engagement with the lug to hold the butt-end of the backing or cover from rising. The backing or cover may readily be detached from the bristle-block after the handle has been unscrewed sufficiently to uncover the lug. This 110

permits effective cleansing, etc., of the upper portion of the bristle-block and the interior of the backing or cover. Afterward the backing or cover may quickly and conveniently be replaced and secured in place again.

- The described construction is simple and practical, and the bristle-block and backing or cover are capable of being manufactured with great facility and at small cost. Since the main portion of the bristle-block is enclosed and concealed by the backing or cover, the expense of finishing, etc., the same to render it presentable and attractive is saved. This is an important item, in view of the fact that the bristle-block is to be discarded as soon as its bristles get in poor condition through use, and a fresh one substituted.
- While the invention is more especially designed as an improvement in tooth-brushes, it is not necessarily restricted in its application solely to brushes for tooth-cleaning purposes.
- What is claimed as the invention is,—
1. In a brush, in combination, a bristle-block having a projecting stem and a verti-

cal outer edge with a projecting flange or shoulder, a backing or cover having a vertical flange which embraces said vertical edge of the bristle-block, with the lower edge of said flange concealed and protected by said projecting flange or shoulder, said backing or cover having a lug, and a handle having a socket in which said stem and lug are removably received and secured. 30

2. In a brush, in combination, a bristle-block having a projecting stem and a plain outer edge with an outwardly projecting flange forming a shoulder, a backing or cover having a plain flange which embraces said plain outer edge of the bristle-block, with its lower edge concealed and protected by the said shoulder, said backing or cover having a lug, means engaging the said backing or cover to hold the same in place upon the bristle-block, and a handle engaging said stem and lug to combine and connect the parts. 40 45

In testimony whereof I affix my signature in presence of two witnesses.

EDGAR G. HUBBEL.
